UNITED STATES PATENT OFFICE.

LAURA GARDIN, OF WESTPORT, CONNECTICUT.

DESIGN FOR A MEDAL, MEDALLION, OR WATCH-CHARM.

46,399.

Specification for Design.

Patented Sept. 15, 1914.

Application filed July 24, 1914. Serial No. 852,914. Term of patent 14 years.

To all whom it may concern:

Be it known that I, LAURA GARDIN, a citizen of the United States, residing at Westport, in the county of Fairfield and State of Connecticut, have invented a new, original, and ornamental Design for Medals, Medallions, or Watch-Charms, of which the following is a specification, reference being had to the accompanying drawing, forming part thereof.

The figure is a plan view of a medal, medallion or watch charm, showing my new design.

I claim:

The ornamental design for a medal, medallion or watch charm, as shown.

LAURA GARDIN.
